UNITED STATES PATENT OFFICE

165,610

FOOD WASHING AND STORING CONTAINER OR SIMILAR ARTICLE

Harry O. Sandberg, Boston, Mass.

Application May 3, 1951, Serial No. 15,059

Term of patent 7 years

(Cl. D58—12)

To all whom it may concern:

Be it known that I, Harry O. Sandberg, a citizen of the United States, residing at Boston, in the county of Suffolk, in the Commonwealth of Massachusetts, have invented a new, original, and ornamental Design for a Food Washing-and-Storing Container or Similar Article, of which the following is a specification, reference being had to the accompanying drawing, forming a part hereof.

Fig. 1 is a perspective view of a food washing-and-storing container or similar article, embodying my new design; and

Fig. 2 is a perspective view of the bottom portion only of the said container.

I claim:

The ornamental design for a food washing-and-storing container or similar article, substantially as shown.

HARRY O. SANDBERG.
